CLAIM

The ornamental design for a clipboard, as shown and described.

DESCRIPTION

FIG. 1 is a top-facing perspective view of a clipboard showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The circular broken lines in the FIGS. 1 and 6 define the bounds of the claimed design and form no part thereof. The straight broken lines in FIGS. 1 and 6 are included for the purpose of illustrating a sheet of paper and form no part of the claimed design.
